UNITED STATES PATENT OFFICE.

RICHARD K. HOHMANN, OF PERU, INDIANA.

BOBBIN CASING AND CARRIER FOR ROTARY-HOOK SEWING MACHINES.

Application filed February 28, 1921. Serial No. 448,577.

To all whom it may concern:

Be it known that I, RICHARD K. HOHMANN, a citizen of the United States, and residing at Peru, Miami County, State of Indiana, have invented certain new and useful Improvements in Bobbin Casings and Carriers for Rotary-Hook Sewing Machines, of which the following is a specification.

10 This invention relates to the rotary hook mechanism of sewing machines and constitutes an improvement on the type disclosed in my pending application, Serial Number 224,002, filed March 22, 1918, and in my Patent 1,364,279, issued January 4, 1921. It resides principally in the structure and arrangement of the bobbin carrier and its casing which make it possible to use a hook member of less diameter and peripheral speed compared to the diameter of the carrier and its bobbin than heretofore, or to use a larger carrier and bobbin without increasing the diameter or peripheral speed of the hook member. As is well known too great peripheral speed of the hook member is objectionable, and for that reason its diameter should be as small as possible, but normally its diameter cannot be reduced without reducing the size of the bobbin and that reduction would be objectionable. The invention also includes co-operating means for locking the bobbin carrier and casing against rotation while guiding one branch of the thread loop around it. The novel features will be more fully understood from the following description and claims taken with the drawings. In the drawings:

Figure 1 is a front elevation of the parts assembled including the hook, the carrier and the casing with a bobbin in place.

Figure 2 is a central vertical section taken at right angles to Figure 1.

Figure 3 is a detached perspective view of the hook member and its spider for connection to the shaft.

Figure 4 is a perspective view of the bobbin carrier; and

Figure 5 is a perspective view of the bobbin casing.

As shown in the drawings a spider 10 has a cylindrical central bushing 11 for attachment to a rotary shaft below the bed plate of the machine as will be understood by those skilled in the art, and has radiating arms 12 with outer portions 13 projecting

forwardly concentric with the bushing and carrying at their ends an incomplete ring section 14 constituting part of the hook ring, the hook itself being at the point where a part of the ring is missing a short distance behind the end 15. A groove 16 is formed on the inner surface of this ring at its end to receive and serve as a bearing for a rim on the bobbin carrier. The outer open side of groove 16 is closed by a semicircular plate 17 fitting against and secured to the end of ring 14 starting at the end 15 and extending around throughout considerably more than half the circumference. The semicircular plate 17 has on its outer face a projecting semicircular flange 18 rising on a gradual incline from the surface at its end 19 to full height and extending around to 20 with its inner wall concentric with the inner edge of plate 17 and its outer wall at the end 19 tapering inwardly to guide the loop of thread. The hook member 21 is shaped to form a continuation of flange 18 but is curved slightly outward and carries hook 22 at its end. The strip 23 spans the opening in the ring section 14, and extends over the inner portion of the hook.

The carrier 24 shown in Figure 4 has a rim 25 fitting in the groove 16 to permit turning of the hook ring around it and is provided with a semicircular projecting flange or portion 26, the ends of which serve as stops as hereinafter explained, and which carries at its outer margin in a plane at right angles to the axis a projecting plate like extension 27 having on it spaced tapering ribs 28.

That portion of the carrier rim 25 and flange extension 26 behind the central portion of plate 27 are removed at 29 to permit the entrance of the needle and thread loop. The ribs or stops 28 cooperate with means not shown for preventing the carrier from rotating with the hook. A post or pin 30 is mounted on the end plate 31 of the carrier 24 to receive the cylindrical central portion of the bobbin casing or holder. This post is not however mounted at the exact center of rim 25 but at a point below and to the right at an angle of about forty-five degrees as will be seen by reference to Figures 1 and 2, so that the center line of post 30 will be eccentric to the center line of the drive shaft and to the path of the hook. The center point for the matching inner surface of groove 16 and outer surface of rim

25 is indicated in Figure 1 at *a*, whereas the center of post 30 and of the outer wall of the bobbin casing which fits on it is indicated at *b*. Broadly considered, this offsetting 5 or eccentric arrangement of the bobbin and its casing in reference to the path of the hook is well known in the art and is for the purpose of allowing room or clearance for the needle at the top, and particularly to 10 provide for the proper angle on the guide surface from the periphery to the end of the holder just beyond the needle to properly spread the loop and cause it to pass around the holder. The necessity for this 15 offset and clearance has in all forms in which it has heretofore been used placed what was considered a fixed maximum limit on the size of bobbin which could be successfully used with a carrier and hook ring 20 of a particular diameter, and conversely has prevented any reduction in the diameter of the hook ring and its relative peripheral speed compared to the rate of revolution when used with a bobbin of definite 25 size. I have however discovered means by which the diameter of the hook ring may be reticized with a bobbin of fixed size or the diameter of the bobbin increased with a hook ring of definite size by an amount 30 equal to the thickness of the bobbin casing while still leaving the necessary offset clearance, and in the form shown it resides in the structural form and cooperative relation of the carrier and bobbin casing which fits 35 in it. It will be noted that while the post 30 is eccentrically arranged in the carrier, the inner wall of the carrier is transversely curved but is longitudinally parallel to post 30 from its outer edge to its base plate 31, 40 and thus forms a substantially cylindrical chamber for the bobbin but of greater diameter, and as will be seen by reference to Figure 2 its depth throughout its circumference between the ends of plate 26 is some- 45 what less than half the length of the cylindrical bobbin casing which fits in it.

The bobbin casing shown in Figure 5 has an outer cylindrical portion or shell 32 and a central sleeve 33 adapted to receive a bob- 50 bin and to fit on the post 30 of the carrier. The material at the inner end of the cylindrical portion 32 is removed to a uniform distance from the end throughout about half of the circumference from the remain- 55 ing end 34 to the end 35, leaving an end margin 36 on that portion in a plane parallel to the plane of the end of the balance of the cylindrical portion, but removed there- 60 from a distance substantially equal to the distance from the outer face of the rim 25 of the carrier to the inner face of bottom plate 31. The offset from center of post 30 and the diameter of cylindrical casing 32 is such that 65 when the casing is inserted in the carrier over post 30 with the full length part at the

upper portion with the ends 34 and 35 on an angle of about forty five degrees upwardly from the left in Figure 1, the full length part will fit within the cylindrical opening in carrier 24 to its base plate, but the margin 36 will abut the outer end face of rim portion 25 and at its central portion its inner surface will be in line with the inner surface of the rim member 25 as shown in Figure 2. It will be observed that this overlapping or alignment of a part of the casing 32 with the rim member 25 instead of fitting entirely within that rim as heretofore renders it possible to use a bobbin casing, and consequently a bobbin, in the 70 particular carrier shown having a diameter greater by an amount equal to the thickness of the casing than would otherwise be possible. That would give the bobbin greater capacity with no change in clearance or diameter of the hook ring or its peripheral speed. To put it differently, the novel construction permits of a greater eccentricity or lateral displacement of the bobbin axis relative to the hook axis than was before 75 possible with the same bobbin and bobbin carrier diameters, and permits of the use of a bobbin of given diameter in a hook ring of smaller diameter than before. While the reduction in diameter by the thickness of 80 the casing and the consequent reduction in peripheral speed of the hook may seem a slight structural change, the increased speed and efficiency of operation resulting from it are in fact very remarkable in practical operation. 85

The cylindrical portion 32 of the bobbin casing has across and secured to its outer end a member 37 which carries at its middle portion sleeve 33 and which extends beyond the margin of the cylindrical portion at the left in Figure 1 and there assumes the form of a flange 38 curved laterally and circumferentially to serve as a thread deflector or guide, and terminating at its upper outer end in a tapered or pointed finger 39. This finger 39 on its inner and under surfaces engages the end 40 of the flange extension 26 to aid in preventing the casing from rotating in the carrier. The member 37 also projects slightly beyond the margin of the casing cylinder at its other end at 41 as shown at the right in Figure 1, and its projecting edge engages the end 42 of the plate extension 26 on the carrier to cooperate with finger 39 in preventing the casing from rotating in the carrier. In Figure 2 an empty bobbin 43 is shown in the casing to illustrate the relations of the parts, and it will be seen that its lower portion extends out substantially to the inner surface of the carrier opening with nothing interposed between, and thus makes contact with that surface. It will be understood by those skilled in the art that in operation the 100

needle descends between plate 27 and the face or plate 17 in Figure 2, and that the loop is there caught by the hook and is carried forward by it, speeding over flange 38 and passing around the bobbin holder mechanism. It operates in a manner well known, and further description is unnecessary.

Having thus described my invention, what is claimed as new and desired to be secured 10 by Letters Patent is:

1. In a rotary hook sewing machine comprising a non-rotatable carrier adapted to be mounted in a rotary hook and formed with a bobbin receiving chamber, a bobbin casing 15 having a bobbin encircling portion cut away at one side and mounted in said carrier with said portion extending into said chamber except at the cutaway side thereof, and with the bobbin axis laterally displaced from the hook axis by a distance greater than would be possible if said casing were not cut away.

2. In a rotary hook mechanism for sewing machines comprising a non-rotatable carrier having a bobbin receiving chamber 25 open at one end and of less depth than the length of the bobbin encircling part which is cut away at one side and is mounted in said carrier with the uncutaway part of said portion extending into said chamber and with the bobbin axis closer to one side of the carrier than would be possible if that side of the carrier were not adjacent the cutaway portion of the casing.

3. Rotary hook mechanism for sewing 35 machines comprising a carrier having a tubular chamber therein open at one end, the wall of which terminates throughout most of its circumference on a transverse plane at the open end, a bobbin casing having a 40 cylindrical shell of less diameter than said chamber, the material at the end of said shell throughout a portion of the circumference extending beyond that of the other portion a distance approximately equal to that of the depth of the chamber from said plane, means for guiding said casing to position with the end portion of greatest length within said chamber extending substantially to the bottom around the upper portion and with the shorter portion of the cylindrical shell abutting the end of the chamber wall at said plane and with its inner surface in line with the inner surface of said chamber on a line at the lower portion, and means for holding said casing in position in said carrier.

4. Rotary hook mechanism for sewing 45 machines comprising a carrier having a tubular chamber therein open at one end, a casing for a bobbin of materially greater length than the depth of said chamber having a cylindrical portion of less diameter than said chamber, means for holding said casing in eccentric position on said carrier 50 with a part of said cylindrical portion abut-

ting at its end an end portion of said chamber wall with the inner surfaces in line along the lower portion and having the opposite side of said casing at and beyond the middle removed inwardly from the carrier's margin a predetermined distance to permit the formation and spreading of the loop.

5. Rotary lock mechanism for sewing 55 machines comprising a carrier having a rim and a bobbin casing extending within said carrier throughout part of its circumference and eccentrically spaced from the rim within that part and abutting the end of the carrier in the opposite part with their inner surfaces in line whereby the bobbin will be in contact on that side throughout part of its length with the casing and throughout the balance of its length with the carrier.

6. In a rotary hook mechanism for sewing 60 machines comprising a non-rotatable carrier having a bobbin receiving chamber open at one end, a bobbin casing comprising a bobbin encircling part which is cut away at one side, and means for holding the bobbin casing in place in the carrier with the outer end portion of the casing at the cutaway side of the latter lying in front of the adjacent portion of the carrier and with the remainder of said encircling portion 65 extending into the chamber.

7. Rotary hook mechanism for sewing 70 machines comprising a carrier provided with a peripheral bearing rim and a concentric chamber closed at its bottom and terminating at its open end throughout most of its circumference at the outer margin of said rim with a depth materially less than the length of a bobbin and having a segmental plate extension at the top, a guide post carried by the bottom wall of said chamber in a position offset downwardly and laterally from the center line of said chamber a predetermined amount, a bobbin 75 casing having a cylindrical shell fitting longitudinally and laterally a bobbin throughout half of the circumference but terminating short of the end throughout a material portion of the circumference by an amount 80 equal to the depth of said chamber, a cross member at the base of said shell carrying a central guide sleeve adapted to fit said guide post, the diameter of said shell being such that when in position on the post the 85 end of the short portion of the shell will abut the outer margin of said rim with the interior surfaces of the shell and chamber in line near the bottom, a thread deflecting flange at one end of said cross member 90 projecting beyond the margin of the cylindrical casing, properly tapered, and provided at its end near and facing the top with a pointed finger adapted at its base to engage one end of said segmental plate 95

extension on the carrier and a projecting portion at the other end of said cross member to engage the other end of said plate extension to hold the casing and carrier in proper position against relative rotation.

8. Rotary hook mechanism for sewing machines comprising a carrier having a chamber therein open at one end with a segmental plate extension at the central upper part over said open end and provided with an upstanding flange and means adapted for engagement to prevent rotation, a cylindrical bobbin casing mounted eccentrically in said carrier away from that portion over which the hook passes first after engaging the loop, a cross member on the end of said bobbin casing extending beyond its margin and beyond the margin of the carrier in the form of a tapering thread guide flange terminating in a pointed finger near the top facing the top and adjacent the

end of said plate extension and abutting said end at its base to prevent rotation, and carrying means at its other end for engaging the other end of said plate extension.

9. A bobbin casing adapted to be removably inserted in the non-rotatable carrier of a rotary hook sewing mechanism and comprising a shell open at its inner end and a post attached to the other end of the shell and adapted to pass axially through a bobbin inserted in the casing, said shell comprising a portion covering the periphery of the inserted bobbin for substantially the full axial depth of the latter at one side of the post and at the opposite side of the post being cut away to expose a considerable portion of the periphery of the bobbin for the purpose specified.

In testimony whereof I affix my signature.
RICHARD K. HOHMANN.
